United States Patent Office

Des. 222,433
Patented Oct. 26, 1971

222,433

BOTTLE

Robert J. Donoghue, 900 Windsor, Ave.,
Windsor, Conn. 06095

Filed Sept. 14, 1970, Ser. No. 24,965

Term of patent 14 years

Int. Cl. D9—01

U.S. Cl. D9—115

FIG. 1

FIG. 5

FIG. 2

FIG. 3

FIG. 4

FIG. 1 is a top plan view of a bottle or similar article embodying my new design;

FIG. 2 is a side elevational view thereof—the opposite side being the same in appearance as the side shown;

FIG. 3 is an end elevational view thereof—the opposite end being the same in appearance as the end shown;

FIG. 4 is a cross-sectional view taken on the line 4—4 of FIG. 2; and

FIG. 5 is a sectional view taken on the line 5—5 of FIG. 2.

I claim:

The ornamental design for a bottle, or similar article as shown and described.
